UNITED STATES PATENT OFFICE.

TOM L. TAYLOR, OF ATLANTA, GEORGIA, ASSIGNOR TO PEARL LAUNDRY MACHINERY COMPANY, OF ATLANTA, GEORGIA, A CORPORATION OF GEORGIA.

LAUNDRY-MARKING MACHINE.

No. 857,421.

Specification of Letters Patent.

Patented June 18, 1907.

Application filed January 20, 1905. Serial No. 242,018.

To all whom it may concern:

Be it known that I, TOM L. TAYLOR, a citizen of the United States, residing at Atlanta, in the county of Fulton and State of Georgia, have invented certain new and useful improvements in Laundry-Marking Machines, of which the following is a specification.

My present invention pertains to improvements in laundry-marking machines, the construction and advantages of which will be hereinafter set forth, reference being had to the annexed drawings, wherein:

Figure 1 is a side elevation, partly in section, of the machine; Fig. 2 a rear elevation 15 of the lower portion of the frame and the type magazine; Fig. 3 a horizontal sectional view, on the line 3—3 of Fig. 1; Fig. 4 a vertical sectional view of the upper portion of the machine, taken on the line 4—4 of Fig. 5; 20 Fig. 5 a top plan view of a portion of the magazine, the chase, platen and inker, the latter being broken away and shown in section in parts; Fig. 6 a transverse vertical sectional view of the platen, taken on the line 25 6—6 of Fig. 4; Fig. 7 a vertical sectional view, on the line 7—7 of Fig. 4, the inker being shown in full lines in its normal position and in dotted lines in its extreme positions; Fig. 8 a side elevation of the inker and chase, 30 looking toward the front of the machine; Fig. 9 a perspective view of a portion of the type-magazine; Fig. 10 a similar view of one of the guide plates; Fig. 11 a like view of one of the type with its attached weight; Fig. 12 a front 35 face view of one of the type, partly broken away, to show the method of attaching the cord thereto; Fig. 13 a vertical longitudinal sectional view of the inker and chase, taken on the line 13—13 of Fig. 5, the inker being 40 shown as thrown down upon the type; Fig. 14 a horizontal sectional view through the outer portion of the inker, on the line 14—14 of Fig. 13; Fig. 15 a transverse vertical sectional view, on the line 15—15 of Fig. 13; Fig. 16 a 45 perspective view of the chase and the attached drum and cams; Fig. 17 a sectional perspective view of the spring-pressed abutment used in the chase; and Fig. 18 a perspective view of the pad contained within the inker and under which the ribbon passes immediately 50 above the type.

The object of my invention is to provide a simple and efficient laundry-marking machine that may be used in connection with any class of work, and which will so imprint the goods as to insure a permanent marking

thereon. The construction is such that the machine may be used by an unskilled operator with little or no danger of the parts becoming disarranged or the type injured or lost.

Referring to the drawings, A designates the pedestal or base of the machine, to which is secured a frame B, preferably formed of a single casting and open at the rear portion. Secured to said frame is a type magazine or case C, which, as will be seen upon reference to Figs. 1, 3, 4, 5 and 9, is composed of a series of boards secured to each other, the boards being each formed or provided with a series of grooves or channels D, extending throughout the length thereof, the outer face of each board forming a closure for the channels next adjacent thereto, with the exception of the outermost, which is provided with a cover board E.

As will be noted upon reference to Figs. 1, 4, 7 and 9, the boards are of different lengths, the shortest being secured to the front face of the frame, so that a series of steps or banks is formed, extending upwardly toward the rear of the magazine or case. The vertically-disposed grooves or channels in each bank or step are substantially closed by a cross-piece or guide-plate F (see Fig. 10), preferably formed of indurated fiber and held in place by pins G, which extend upwardly at each end of the series and make a close fit with an opening H formed adjacent to each end of the plate. The plate is likewise provided with a series of key-hole slots I, one for each of the channels, the upper edge of the rounded portion of each slot being slightly flared or curved so as to permit the cord J of the type K to pass freely therethrough without danger of cutting or undue wear. To the lower end of the cord is secured a weight L, which works up and down in the groove as the type is withdrawn from its normal upright position to the chase and by the chase carried from a position under the inker over to the printing position, as shown in dotted lines in Figs. 1 and 4, or returned to its initial position.

The type are of the form best shown in Fig. 11; that is, they are T-shaped, with the type-face formed upon a laterally-projecting arm so that the face stands in full view of the operator of the machine, as will be noted upon reference to Fig. 7. The lower portion of the type is provided with a cross opening M, and a smaller opening N which

extends at right angles thereto and opens out through the bottom of the type. This construction permits the cord to be passed through the smaller opening and out through opening M for the formation of a knot, which may afterward be withdrawn into the body of the type or into the opening M, as clearly shown in Fig. 12. The cord employed is preferably formed of twine or the like, thoroughly impregnated with wax to prevent wear and avoid undue friction as the cord works through the slot I. The face of the type will be comparatively sharp and the sides thereof given an inclination from the face toward the body portion, the height of the type being sufficient to take up enough ink to thoroughly impregnate the goods as the type is forced into the same in the act of marking. The sharp face of the type will indent the goods to a limited extent and the ink upon the side faces will pass into the fabric by capillary attraction. When the type are freed from the chase they will, by reason of the action of the weights, be drawn back to their normal positions upon the guide-plates or cross-pieces F. A bed plate O is secured to the frame or casting B by brackets P, and upon this bed plate is mounted a movable chase, an inking mechanism and the combined platen and clamp for the goods.

Q designates a box-like frame, having secured to its upper face a plate Q' provided at its outer end with a lip R, the outer end of said lip being curved upwardly, as will be seen upon reference to Fig. 1. Plate Q' is likewise provided with an elongated opening S (Fig. 5), which permits a line of type to pass through the same and to come into contact with the goods placed thereunder and held close against the under face of the plate or lip by a vertically-moving platen and clamp T. Said platen, as will be seen upon reference to Figs. 4 and 6, is composed of a plate which lies immediately below the lip or clamping plate Q' and is provided with a yielding block U, secured in its upper face immediately below the opening S. Normally the platen is forced up toward the plate Q' by springs V which encircle the reduced portion of the guiding-posts or stems W, said posts working in ways or barrels X formed in the box or frame Q. Springs V, as will be seen upon reference to Fig. 6, bear at their lower ends against the closed ends of the barrels or ways X and thereby normally press the platen up toward the clamping plate Q'. The lower ends of the stems or posts W are connected by a cross-bar Y, and a lever-frame Z (Fig. 4) fulcrumed at A', rests upon the upper side of said cross-bar. Lever-frame Z is provided with two upwardly-projecting lugs or arms B' (see Fig. 7) intermediate which is journaled a roller C', said roller standing in line with cams D'

formed as integral parts of the drum E' of the chase (see Fig. 16). Said drum is provided with laterally-extending pintles (or an axle) F', which travel in lugs G' extending upwardly from the plate Q'. The drum is also provided with lugs H', H', and a sprocket-chain I' is passed over the drum, the lugs H' entering the open links of the chain. Said chain is secured at one end to a long coiled spring J', the opposite end having secured to it a link or rod K' which is attached at its lower end to a treadle L', fulcrumed at M' at the rear of the pedestal A. The spring normally holds the treadle in its elevated position and consequently maintains chase N' (which is attached to the drum E' by the intermediate arm O') in the position shown in Figs. 1, 4 and 5. Or in other words, holds it in that position where it lies immediately below the inker frame. When the chase is in this position, the cams D' acting on the roller C' throw the lever frame Z downwardly and, acting through the cross-bar Y, withdraw the platen from the clamping plate or lip R, or into the position shown in Figs. 4 and 6. Plate Q' is provided with a yielding block P', preferably formed of rubber, said block lying immediately below the chase N' when the latter is in its rearmost position. This block tends to absorb any shock or jar caused by the return movement of the chase through the action of the spring J'.

The main body of the chase is formed as an integral portion of the arm O', the outer end being curved, as clearly indicated at R' in Figs. 13 and 16, and provided with a transverse opening adjacent to said curved portion through which extends the nose S' of a spring-pressed latch T', fulcrumed in the chase at U'. The nose of the latch is inclined upwardly away from the curved portion R' of which it may be said to form a continuation. The latch is provided with an outwardly-extending finger-piece V' by which the latch may be withdrawn when the chase is elevated to a slight extent, or when the screw W', carried by the latch, is sufficiently withdrawn from contact with the block P'. The inner square face of the nose S' works in conjunction with a spring-pressed abutment X' and the fingers Y', Y' which extend forwardly from plate Z', said fingers standing at a slight distance above the body of the chase or at a height equal to the thickness of the body of the type. The fingers are separated from each other a distance equal to the width of the lateral projection or arm of the type, and the upwardly-extending portion of the abutment X' is also of a width substantially equal to the distance between the inner faces of said fingers. Said abutment X', as will be seen upon reference to Figs. 13 and 17, is composed of two telescoping tubes A², B², mounted within the chase and normally extended by a spring C², which

bears at one end against the abutment and at the other against the downwardly-projecting member of the plate Z'. A post D² is secured to said plate and extends inwardly therefrom through a portion of the coiled spring C², in order to prevent said spring from buckling as it is compressed.

As will be readily appreciated, any desired type may be withdrawn from its position in the magazine or holder and pressed upon the inclined face of the nose S' and the under face of the fingers Y', Y'. A continued movement of the type will depress the nose and permit the type to pass in against the abutment X'. Immediately the type has cleared the nose, its spring will force the same upwardly against the side face of the type, which is thus securely held between the abutment and the flat face of the nose and beneath the fingers Y', Y'. Any number of type may thus be secured in place, three being shown in Fig. 13. The spring-pressed abutment will hold the type close to each other and firmly against the vertically-disposed face of the nose S'. When it is desired to release the type, the finger V' of the latch is depressed, withdrawing the nose from contact with the type and permitting the spring-pressed abutment or follower to force the type outwardly from beneath the fingers Y'. As the type are freed from the fingers, the weights will cause the same to be drawn back to proper positions in the case or magazine.

A downward movement of the treadle will cause the chase to move from the position shown in full lines in Fig. 4 to the dotted line position indicated in said figure. As this is done the weights attached to the type secured in the chase will be elevated and as the drum E' rotates, the cams D' thereof will move out of contact with the roller C' and permit the lever-frame Z to be moved upwardly by the action of the springs V, thereby permitting the platen to move upwardly and clamp the goods resting thereon between it and the plate or lip. The goods are clamped previous to the type carried by the chase coming into contact therewith. The yielding member or block U of the platen permits the type to make a deep impression if so desired. The degree or extent of the impression may be regulated by the amount of pressure exerted upon the treadle. The goods may thus be marked light or heavy, but in each and every instance the impression is sharp and well-defined.

In order to automatically ink the type, I employ an inker such as is shown in detail in Figs. 5, 7, 8, 13, 14 and 15. The body of the inker comprises a hollow casting having an enlarged ink-containing chamber E², with a laterally-projecting arm F². Extending outwardly from the hollow chamber or body portion of the inker are stud-axles G², see Fig. 15, said axles resting in sockets or re-

cesses formed in vertically-disposed arms H² of a pivoted bracket I², fulcrumed at J² upon lugs or ears K² extending outwardly from the box-like frame or casting Q. To adjust the bracket I² and secure it in such position, I employ an adjusting screw L² and a locking screw M², the latter passing through a slot or opening formed in the lower end of the bracket and being screwed into the frame or casting Q. By shifting the bracket, the arm F² may be given proper adjustment relative to the face of the type carried by the chase. To hold the stud-axles G² in place, I employ cap pieces N², see Figs. 8 and 15, which overlie the stud-axles at the upper end of the recesses in which they rest, said cap pieces being secured to the arms H² by screws O². A spring P² is secured within the ink-chamber E², the outer end of the spring being bifurcated and turned back upon itself, forming journals for the stud-axles of an ink-applying and distributing disk or wheel Q². Pivotally secured to spring P² is an arm P⁴, provided with a head P⁶ which extends into a recess formed in the body of the inker. A screw P⁸, acting on said head enables one to adjust the degree of pressure of the disk upon the inking ribbon, or to withdraw the disk entirely, in case the ribbon should become supersaturated. A ribbon R² is mounted within the upper portion of the chamber E² and extends throughout the length of the arm F². It passes about a roll S² having a roughened face to insure proper feed of the ribbon (see Fig. 15), over an idler roll T², around a roll U² mounted at the extreme outer end of arm F², and above and below an intermediately disposed roll V². Roll S² is secured upon a shaft W², upon which shaft is journaled a ratchet-wheel X². Between the ratchet-wheel X² and the adjacent face of the chamber E² is a pawl-carrier Y², having at its upper end a pawl Z², which normally stands in engagement with the teeth of the ratchet-wheel X², as will be seen upon reference to Fig. 8. The pawl-carrier has the form of an elbow lever and the forwardly-extending arm thereof is pivotally connected to the upper end of a link A³, the lower end of which is pivoted to the bracket I². The pivotal point of connection between the link and the forward end of the pawl-carrier may be changed and the degree of movement imparted to the roll S² thereby altered, which will effect a change in the speed of travel of the ribbon past the opening B³ formed in the lower face of the arm F² in line with the type carried by the chase, see Fig. 13. As the inker is moved downwardly from the position shown in full lines to the dotted line position, Fig. 8, the ratchet-wheel X², shaft W², and consequently the roll S², will be rotated and the ribbon shifted in the direction indicated by the arrows in Fig. 13. Upon the return or upward movement of the inker, the pawl Z² will ride

over the teeth of the ratchet-wheel X^2 and no movement will be imparted to the ribbon.

To prevent the ribbon being cut by the type, and in order to apply a sufficient quantity of ink to the type, I employ a pad C^3 , shown in detail in Figs. 14 and 18. This pad comprises a block, preferably of metal, cut away at that portion which is in line with the path of travel of the ribbon, and about this cut-away portion are wound and secured several layers of fibrous material. The block or pad is let into the side of arm F^2 through an opening provided for that purpose, the flanged head E^3 of the block forming a tight joint with the wall of the arm, while pins F^3 , which enter the opposite wall of the arm, properly position the block. Screws G^3 , see Fig. 8, are passed through the wall of the arm F^2 and into the block, thus securely holding it in place. An opening is formed in the upper portion of the arm adjacent to its junction with the body portion of the ink-containing chamber E^2 for the introduction of ink thereto, and a slide or cover H^3 , normally held in its closed position by a screw or similar fastening device I^3 , is provided for said opening. A scraper J^3 is pivoted in the inker below the cover H^3 , its curved forward end resting upon the ribbon and tending to remove any surplus ink therefrom. Said scraper carries an adjustable screw K^3 , the head of which comes into contact with the cover H^3 , whereby the scraper is forced downwardly upon the ribbon to a greater or less extent as occasion may require. A counterweight L^3 is pivotally connected to the upper rear portion of the inker, said weight being cut away so as to embrace or straddle the body of the inker and the lug to which it is attached. The inner face of the counterweight is provided with an elastic lining or cushion M^3 , Fig. 13, so as to take up any jar or strain to which the parts would otherwise be subjected. Lugs or ears N^3 extend outwardly from the body E^2 of the inker and a link O^3 is pivotally connected thereto. Said link in turn is connected to a rod P^3 , the lower end of which is threaded and passes through an opening formed in a lateral projection Q^3 of an arm or rod R^3 , the upper end of which is bent at right angles and passed through one of the open links of the sprocket-chain I' . A cotter pin S^3 is passed through the end of the arm upon the opposite side of the chain in order to prevent withdrawal of the arm from the chain. The rod R^3 passes through a guide or bracket T^3 secured to the frame B . A nut and jam nut are mounted upon the lower end of the rod P^3 , beneath the arm or lateral projection Q^3 , see Fig. 7. The inker is likewise provided with stops U^3 which, under certain conditions, abut against shoulders V^3 formed upon the bracket I^2 . A shield or cover W^3 is provided for the end of the

shaft W^2 (see Fig. 15), said cover serving in a measure to prevent leakage of ink over the outside face of the inker if any should work out past the shaft.

Normally the inker stands in the position shown in full lines in Figs. 7 and 8. In order to give the type their first inking after they are set up in the chase, it is necessary to depress the treadle and then allow it to move upwardly, which has the effect of rotating the chase about the stud-axes G^2 and permitting it to again swing rearwardly, at which time the arm Q^3 comes into sharp contact with the nuts upon the rod P^3 , whereby the inker is thrown downwardly upon the face of the type or into the position shown in dotted lines in Fig. 7. Immediately, however, the ink has been deposited upon the type, the inker is moved upwardly into the position shown in full lines in Fig. 8 through the action of the counterweight L^3 . It remains in this position until the chase is thrown forwardly in the act of causing an impression. At this time, the arm Q^3 is moved up into the position shown in dotted lines Fig. 7, and the rod P^3 will likewise move up to the position indicated in dotted lines, permitting the inker to assume the position shown in the uppermost dotted lines, at which time the stops U^3 will come into contact with the shoulders V^3 , and prevent further movement. When the treadle is again released and the spring J' comes into action, the chase is turned to a position where the type will again be in the path of the inker, and by reason of the arm Q^3 coming into contact with the nuts upon the rod P^3 the inker will again be thrown down and supply the type with ink. The inker may be said to deliver a blow upon the type-face, which has the effect of thoroughly inking the type, both upon the sharp outer face thereof and to a greater or less extent upon the side faces of the type. In delivering the fresh ink to the type, the inker is suddenly arrested by its contact with the type, and it is for this reason that the counterweight L^3 is pivotally connected to the inker. As will be seen, the counterweight will have a movement independent of that of the inker, and too great a blow is thus prevented from being delivered to the type face.

No claim is herein made to the inking apparatus *per se*, as that forms the subject-matter of my co-pending application Serial No. 265,620, filed on or about the 16th day of June, 1905, the same being a division of this application.

Having thus described my invention, what I claim is:

1. In a machine of the character specified, the combination of a type magazine or case; a series of banks of type mounted thereon; means for normally holding said type in position and returning them when unrestrained.

- a chase; means for holding the type in the chase; a platen; and means for moving the chase with the type therein toward the platen. 65
- 5 2. In a machine of the character specified, the combination of a type magazine or case; a series of type mounted thereon, each type having a weight attached thereto by a cord; a chase; means for securing the type within the chase; a platen; and means for moving the chase with the type therein over toward the platen. 70
- 10 3. In a machine of the character specified, the combination of a type magazine or case; a series of type mounted thereon; a weight suspended from each type by a cord; a chase adapted to hold the type; a platen; means for moving the chase over toward the platen; and an automatic inking mechanism adapted 75 to apply ink to the face of the type. 80
- 15 4. In a machine of the character specified, the combination of a type magazine or case; a series of type mounted thereon; a weight suspended from each of said type by a cord; a chase; a platen; means for moving the chase with the type therein over toward the platen; means for clamping the goods to be marked upon said platen; and an automatic inking mechanism adapted and arranged to 85 apply ink to the type in the chase, substantially as described. 90
- 20 5. In a machine of the character specified, the combination of a type magazine or case; a series of type mounted thereon; a weight suspended from each of said type by a cord; a platen; a chase located intermediate said magazine and the platen; means for moving the chase toward and from the platen; an inking device; a clamping device for the 95 goods to be marked; and means under the control of the operator for moving the chase toward the platen, clamping the goods, and causing the inking mechanism to come into operation upon the return of the chase from the platen. 100
- 25 6. In a machine of the character specified, the combination of a type magazine or case having a series of channels formed therein; a series of type arranged in banks or steps; a series of guide-plates or bars extending across said channels, each plate having a series of holes or slots formed therein in line with the channels; a series of cords, one for each type, said cords passing through the holes or slots 105 in the bars; a weight attached to each of said cords; a chase; a platen; and means for moving the chase toward and from the platen. 110
- 30 7. In a machine of the character specified, the combination of a type magazine or case having a series of channels or grooves formed therein which terminate at different heights, thereby forming steps; a cross-bar for each step, said cross-bars each being provided with a series of key-hole slots in line with the 115
- 35 channels or grooves beneath the same; a series of type; a cord extending from each type through a key-hole slot into a channel; a weight connected to the lower end of each cord; a chase; a platen; and means for shifting the chase toward and from the platen. 120
- 40 8. In a machine of the character specified, the combination of a type magazine or case; a series of type mounted thereon; means for normally holding said type in normal position with reference to the magazine and returning them to such position when not restrained; a chase; means carried by the chase for holding the type in position thereon; a platen; means for oscillating the chase toward and from the platen; a clamp for the goods to be marked; an inking device pivotally mounted to one side of the chase; and means for throwing the inking device down upon the type as the chase is brought to its rearmost position, substantially as described. 125
- 45 9. In a machine of the character specified, the combination of a type magazine or case; a series of type mounted thereon; a cord attached to each type; a weight secured to each cord; a chase; means carried by the chase for retaining the type thereon; a platen; means for oscillating the chase toward and from the platen; an inker pivotally mounted to one side of the chase; a counter-weight for normally holding said inker in its elevated position; and a device intermediate said inker and the means for oscillating the chase for depressing the inker as the chase is swung rearwardly away from the platen. 130
- 50 10. In a machine of the character specified, the combination of a type magazine or case; a series of type carried thereby; an oscillating chase; a drum connected to the chase; a chain passing about the drum; a spring connected to one end of the chain and to a fixed portion of the machine; a treadle connected to the opposite end of the chain; an inker pivotally mounted adjacent to one side of the machine; and connections intermediate said inker and the actuating device for the chain, whereby the inker will be thrown down upon the type carried by the chase as the chase is moved to its rearmost position, substantially as described. 135
- 55 11. In a machine of the character specified, a chase comprising a main body, retaining fingers extending outwardly over said body, a spring-pressed latch, and a spring-pressed abutment or follower normally forced toward said latch in line with the fingers, substantially as described. 140
- 60 7. In testimony whereof I have signed my name to this specification in the presence of two subscribing witnesses.

TOM L. TAYLOR.
